DERRICK STRUCTURE

William Schwemlein, Parkersburg, W. Va., assignor to The Parkersburg Rig & Reel Company, Parkersburg, W. Va., a corporation of West Virginia.

Continuation of application Serial No. 74,777, April 16, 1936. This application January 18, 1938, Serial No. 185,618

6 Claims. (Cl. 189—16)

This invention relates to derrick structures and is a continuation of my copending application Serial No. 74,777, filed April 16, 1936.

Oil well derricks are commonly constructed along conventional lines which are well known, such derricks comprising four legs suitably braced with respect to each other with each of the legs formed straight from end to end. Such a derrick is commonly provided adjacent its upper end with a crown platform surmounted by the usual gin pole, and at the proper height above the derrick floor the derrick supports a working platform.

It is the usual practice, for example in deep well rotary drilling, to rack several stands of drill pipe in a vertical position within the derrick. Each stand of pipe usually is 90 feet long, being made up of three 30 foot sections, and the stands of pipe rest upon a pad on the derrick floor and 15 lean against what is known as a "fourble board" at the elevation of the derrick platform.

The successive stands of pipe are added to the pipe sections extending into the well, and it is necessary for the drilling crew to shut down actual drilling whenever it is necessary to rack additional stands of pipe. Accordingly it is desirable to stack as many stands of pipe as possible to avoid the delay and expense incident to frequent shut-downs.

Derricks have been conveniently made 222 feet in height, but with the increase in deep well drilling it has been found that there is not sufficient space at the working platform to accommodate the desirable number of stands of pipe. Accordingly derricks employed in deep well drilling have been increased to a height of 136 feet and by such increase of 14 feet in the height of the derrick a gain of only 1 foot in space is obtained at the working platform to accommodate 25 the pipe stands. Obviously the increase in the cost of the higher derrick is substantially out of proportion to the relatively minor advantages obtained from its use. This problem has been under discussion by leading engineers in the industry and no satisfactory solution of the problem has been obtained.

An important object of the present invention is to provide a derrick structure of the character indicated wherein substantially greater space at 30 the working platform is obtained without substantially increasing the cost of the derrick.

A further object is to provide a derrick structure wherein increased space for the pipe stands is obtained at the working platform without increasing the height of the derrick.

A further object is to provide a novel derrick structure wherein the conventional straight-legged derrick is departed from by providing a plurality of legs each of which is slightly angled at the height of the working platform to increase 5 the available space for pipe stands without increasing the height of the derrick.

A further object is to provide a derrick structure which tapers in different degrees above and below an intermediate point at the height of the 10 working platform, the degrees of taper above and below such intermediate point being respectively greater and less than the taper of a conventional derrick.

Other objects and advantages of the invention 15 will become apparent during the course of the following description.

In the drawing I have shown one embodiment of the invention. In this showing—

Figure 1 is a side elevation of the improved 20 derrick structure.

Figure 2 is an enlarged fragmentary side elevation of a portion of the derrick structure at the height of the working platform, the latter being omitted.

Figure 3 is a section on line 3—3 of Figure 2, and,

Figure 4 is a detail sectional view on line 4—4 of Figure 1, the working platform and all braces and girts being omitted for the purpose of illustration.

Referring to Figure 1, the numeral 10 designates the derrick structure as a whole which is made up of a plurality of fabricated legs 11 which may be four in number in accordance with the 35 usual practice. Each of the derrick legs is made up of lower sections 12 extending from the derrick floor 13 to the point at which the working platform 14 is supported. Each derrick leg further includes an upper section 15 extending from the working platform to the crown platform 16 which is of the usual type supported at the top of the derrick. Any desired form of gin pole 17 is supported by the upper end of the derrick and projects upwardly above the crown platform in 40 the usual manner. The legs of the derrick are braced with respect to each other at suitable points by girts 18 and braces 19, most of these bracing elements being of the conventional type and connected to the derrick legs and to each 45 other in the conventional manner.

The upper and lower sections of each leg 11 are arranged at a slight angle with respect to each other as indicated in Figures 1 and 2, the broken lines 19' being in alignment with the leg 55

sections 12 and indicating the angularity between the leg sections 12 and 15. The adjacent ends of the legs are cut at the proper angle to abut as indicated by the numeral 20 whereby the 5 leg sections are firmly seated with respect to each other. An outside splice plate 21 assists in bracing the adjacent leg sections with respect to each other. This splice plate is of angular section as clearly shown in Figure 3 and is slightly 10 angled intermediate its ends on both faces as at 22 so that its upper and lower end portions fit against the faces of the adjacent end portions of the leg sections 12 and 15. The line of the angles 22 of the splice plate 21 and the abutting edges 20 of the leg sections lie in a common 15 plane as will be apparent. It will be apparent that both sections 12 and 15 of each leg 11 lie in a single plane which is in a common plane with the diagonally opposite leg 11. The arrangement 20 of one leg section 15 above its associated leg section 12 is indicated in Figure 4.

Inside splice bars 23 are arranged against the respective inner faces of the two abutting leg sections and each splice bar 23 is likewise angled 25 in the plane of the abutting edges 20. The respective leg sections, the splice plate 21 and the splice bars 23 are secured by bolts 24 extending therethrough. Accordingly these elements are firmly anchored with respect to each other. The 30 lower end of each leg section 15 is slotted as at 26 to receive one of the bolts 24 at each side of the derrick to facilitate assembly of the parts.

To add increased rigidity to the elements described, it will be noted that the adjacent pairs 35 of legs 11 are braced with respect of each other by girts 25, similar to the girts 18 commonly employed in derrick structures. Each girt receives one of the bolts 24 and is further secured to its adjacent splice plate 21 by at least one additional bolt 27. Certain of the diagonal braces 19, such as the braces 28 in Figure 2, have one end secured in position by certain of the bolts 24, and each of these braces is further secured in position by at least one additional bolt 29 passing through each 40 brace and the adjacent splice plate 21. The ends of the braces 28 opposite their connection with the splice plates 21 are secured to the derrick leg sections in the usual manner.

The working platform 14 has been omitted 50 from Figure 2 for the purpose of illustration. This platform per se may be conventional in construction and is supported with respect to the derrick in any suitable manner, as for example, by means of the horizontal girts 25. It is 55 from this platform that the pipe stands are handled in the usual manner, and one of these stands has been indicated in position in Figure 1 and designated by the numeral 30. As is the common practice, this pipe stand is indicated as 60 being made up of three pipe sections 31, although it will be obvious that the present invention is not concerned in any manner with the particular form of pipe stands.

The derrick structure is adapted for the same 65 uses as the conventional derrick structures and has substantial advantages thereover. It will be apparent from Figure 1 that if the upper leg sections 15 were arranged in alinement with the lower leg sections 12, as suggested by the broken 70 lines 19', the derrick would extend to a substantially greater height before reaching the proper size at the upper end of the derrick. Such additional height would be useless except to provide the desired derrick size at the working platform 75 and would involve a substantial increase in the

cost of building and erecting the derrick. As previously stated, derricks of increased height have been restored to almost solely for the purpose of providing for an increased number of stands of drill pipe, it being considered necessary in the 5 art to form the derrick legs straight from end to end. The highly desirable results of the present construction are obtained by tapering the derrick above the working platform to a degree greater than the taper in the conventional derrick and by 10 tapering the derrick below the working platform to a degree less than the taper of a conventional derrick.

In this connection it would be assumed that the break in the continuity of each derrick leg 15 would substantially weaken the structure of the derrick, but in practice this has been found not to be the case. The derrick structure described possesses at least the strength of conventional derrick structures. As a matter of fact, since the 20 lower leg sections 12 are more nearly vertical than in conventional constructions, the stresses on all of the girts and diagonal braces below the working platform are reduced.

While a derrick constructed in accordance with 25 the present invention is slightly more expensive than a conventional derrick of the same height, it effects a substantial economy over the cost of a higher derrick of conventional construction having the same advantages with respect to the 30 stacking of stands of pipe at the working platform. The provision for stacking an increased number of pipe stands obviously reduces the frequency with which the drilling operation ordinarily is stopped to permit the racking of additional stands of pipe.

The use of the splice plates 21 and splice bars 23 provides adequate bracing means between the adjacent leg sections and the use of girts 25 approximately in the horizontal plane at which the angles occur in the several legs effectively prevents the spreading or buckling of the legs. Thus it will be apparent that the structure provides substantial advantages over prior constructions without sacrificing any of the necessary structural strength.

As previously stated, both sections 12 and 15 of each leg 11 lie in a common plane with the sections of the diagonally opposite leg 11. The common planes of the diagonally opposite legs intersect along the vertical axis of the derrick. Accordingly it will be apparent that the vertical plane of each leg is coincident with the axis of the derrick, and accordingly vertical strains are taken up by the legs in the vertical planes of the neutral axes of the angle sections from which the legs are fabricated.

Since the drill pipe is usually racked on only one side of the derrick, it will be apparent that increased space need not be provided on all four sides. Accordingly the present invention contemplates making one or more sides of the derrick in accordance with the angular leg arrangement shown in Figure 2. In other words, the present invention contemplates constructing at 60 least one side of the derrick in the manner stated although it is preferred that all of the legs of the derrick be made in sections slightly angled with respect to each other, since such construction possesses obvious advantages as to strength 65 and stability.

It is to be understood that the form of the invention herewith shown and described is to be taken as a preferred example of the same and that various changes in the shape, size and ar- 70 75

angement of parts may be resorted to without departing from the spirit of the invention or the scope of the subjoined claims.

I claim:

5. 1. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and bracing means for said legs including a girt connected horizontally between each adjacent pair of splice plates. 15
10. 2. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and a working platform arranged adjacent such intermediate point. 20
15. 2. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and a working platform arranged adjacent such intermediate point. 25
20. 3. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and a working platform arranged adjacent such intermediate point. 30
25. 3. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and a horizontal girt connecting each adjacent pair of splice plates. 35
30. 4. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point, bracing means connected between said legs and arranged substantially in said horizontal plane, and a working platform arranged adjacent such intermediate point and carried by said bracing means. 40
35. 4. A well drilling derrick having a plurality of pairs of diagonally opposite legs, each such pair of legs lying in a common plane throughout their height and being slightly inclined toward each other from their lower extremities to a point intermediate their height, and being inclined to a slightly greater extent toward each other upwardly from such intermediate point, the degrees of taper above and below said intermediate point being respectively greater and less than the taper of a conventional drilling derrick, each leg comprising upper and lower sections having their adjacent ends terminating in the horizontal plane of such intermediate point and arranged in abutting relationship, a splice plate secured to the adjacent ends of the sections of each leg, and bracing means for said legs including a girt connected horizontally between each adjacent pair of splice plates. 45
40. 5. A well drilling derrick comprising a plurality of legs each lying in a vertical plane coincident with the vertical axis of the derrick, each leg being slightly inclined inwardly toward such vertical axis from the lower end of the leg to a point intermediate the height of the derrick and being inclined at a relatively greater angle toward such vertical axis upwardly from such intermediate point, the degrees of taper above and below said intermediate point being respectively greater and less than the taper of a conventional drilling derrick, each leg being formed of upper and lower straight sections having their adjacent ends abutting and terminating at such intermediate point, each section being formed angular in cross-section, a splice plate of an angular cross-section corresponding to the angular cross-section of said leg sections and secured to the adjacent ends of the sections of each leg, and a horizontal girt connecting each adjacent pair of splice plates. 50
45. 6. A well drilling derrick comprising a plurality of legs and being relatively slightly tapered to decrease in size from its lower end to a point intermediate its height and being tapered to a relatively greater degree to decrease in size upwardly from such intermediate point, the degrees of taper above and below said intermediate point being respectively greater and less than the taper of a conventional drilling derrick, each leg being formed of a pair of straight sections of corresponding angular cross-section having their adjacent ends arranged in abutting relationship in the horizontal plane of such intermediate point, bracing means connected between said legs and arranged substantially in said horizontal plane, and a working platform arranged adjacent such intermediate point and carried by said bracing means. 55
